UNITED STATES PATENT OFFICE

111,774

DESIGN FOR A DECORATIVE WALL PLAQUE OR ANALOGOUS ARTICLE

Arthur A. Nudell, Chicago, Ill.

Application July 29, 1938, Serial No. 78,961

Term of patent 7 years

To all whom it may concern:

Be it known that I, Arthur A. Nudell, a citizen of the United States, residing at Chicago, in the county of Cook and State of Illinois, have invented a new, original, and ornamental Design for a Decorative Wall Plaque or Analogous Article, of which the following is a specification, reference being made to the accompanying drawing, forming a part thereof.

On the drawing,

I claim:
The ornamental design for a decorative wall plaque or analogous article, as shown.

ARTHUR A. NUDELL.
